MATCH BOOK HOLDER

Benjamin L. Brooks, Lynchburg, Va.

Application April 17, 1940, Serial No. 330,178

2 Claims. (Cl. 206—29)

This invention relates to holders for paper match books, and this application for patent is a continuation-in-part of my application for patent Serial No. 237,640, filed July 31, 1939.

The object of the present invention is to provide a holder into which the conventional paper match book may be easily inserted and readily removed therefrom; which shall firmly hold the match book in position, in resistance to the pull exerted upon it by the act of breaking off a match; which shall be so constructed as to expose the striking surface of the match book, without having any structure at the ends of the striking surface with which the head of the match might collide in the course of its striking movement; which provides a fire guard between the striking surface and the heads of the match; which provides a plate for advertising matter either above or below the fire guard, or in both positions, and which affords a convenient edge for the severance of the cover of the match book.

The invention contemplates a match book holder in which any one or more of these features are embodied.

Referring to the drawings, throughout the several figures of which the same reference characters have been used to denote identical parts, the group of Figures 1 to 4 represent one modification of the invention.

Figure 1 being a perspective view showing the front aspect of the holder;

Figure 2 being a similar view with the match book in place;

Figure 3 being a perspective view showing a rear aspect, and illustrating the severance of the cover of the match book against the top edge of the back plate, and

Figure 4 being a cross-section through the holder taken in a vertical plane.

Figures 5 and 6 are, respectively, a front elevational view and an end view of a slightly modified form of the invention;

Figures 7 and 8 are, respectively, a front elevational view and an end view of still another slightly modified form of the invention;

Figure 9 is a perspective view of a match book holder embodying the principles of the present invention illustrating the ease of removal of a spent match book from the holder.

Referring now in detail to the several figures, and first advertiring to the group of Figures 1 to 4, inclusive, the numeral 1 represents the holder as a whole, which may be made of metal or of any suitable rigid material, comprising a back plate 2, which at its lower end is forwardly and up-

wardly curved or bent to form a trough 3 for receiving the base of the match book. The back plate is provided near its upper edge 4 with spurs 5, which are forced penetrably into the back cover 6 of the match book, for holding the match book in position in the holder. As an auxiliary holding means the back plate 2, at its lateral edges, is provided with the upwardly extending lugs 7, between which the match book is retained.

At its lower portion, the back plate 2 may be provided with the forwardly extending sides 8, the upper front edges of which are bridged by the match book retaining band 9.

This band, as shown, has a forwardly and upwardly turned flange 10, extending transversely across the holder, the function of which flange is as a reinforcing member to increase the rigidity of the holder, and also as a fire guard to deflect from the match heads any spark which may fly from the match which is being struck. The front of the holder is provided with an open space 11 between the fire guard and the trough 3, which open space coincides with the striking area on the front of the match book. It will be observed that the sides 8 are formed with recesses 12 at the ends of the open space 11, and which extend back of the plane of the striking surface of the match book, so that the holder presents no lateral structure in the path of movement of the match being struck and with which, were such structure present, the match head might collide and be broken off.

The retaining band 9 in this form of the invention extends upwardly from the fire guard a sufficient distance to provide a plate 13, affording a support for an advertising label or legend. The back plate 2, trough 3, sides 8, and retaining band 9, form a pocket in which the lower portion of the match book is inserted. After insertion, the match book is pressed against the spurs 5 so that the latter impale the back cover 6 of the match book. The matches themselves form a protection to prevent injury to the fingers when the match book is being pressed against the spurs.

The match book is thus held firmly with respect to the holder, so as to resist displacement from the pull exerted upon the match book when matches are torn or broken therefrom. It has been amply proven by experiment that the spurs alone are quite sufficient to hold a match book in place. However, inasmuch as the presence of the advertising plate 13 determines that the matches will be pulled sideways instead of forwardly, in breaking them off, the lugs 7 may be

useful as an auxiliary holding means to prevent lateral displacement of the match book. It is within the purview of the invention to employ the lugs 7 alone, without the spurs.

In employing this holder, it is generally desirable to tear off the cover of the match book. Figure 3 shows that the top edge 4 of the back plate 2 constitutes a convenient straight edge against which the back folded cover may be forcibly drawn in tearing it off. The match book holder in this form of the invention, as well as in the modifications presently to be described may be conveniently mounted upon any suitable pedestal, such as the stand 14.

Referring now to that form of the invention illustrated in Figures 5 and 6, it distinguishes from the form already described, chiefly in two particulars, that the reinforcing flange 15 which corresponds to the reinforcing flange 10 of that form of the invention described in Figures 1 to 4, inclusive, is bent down and outwardly at a right angle to the retaining band 16. This construction has one advantage over that shown in Figures 1 to 4, in that the fire guard extends out for a greater distance, and therefore, is presumably that much more effective in its function as a fire guard. However, the form shown in Figures 1 to 4, inclusive, may be preferred, for the sloping nature of the flange 10 gives it the function of guiding a match onto the striking surface of the match book, which may have been carelessly applied thereto in the act of striking.

The form of the invention shown in Figures 5 and 6 also omits the advertising plate 13 above the retaining band, and substitutes therefor an advertising plate 17 which extends below the trough 3 within which the base of the match book seats.

That form of the invention shown in Figures 7 and 8 distinguishes from the form of the invention shown in Figures 5 and 6 solely in that it omits any advertising plate either above or below the retaining band.

Figure 9 shows that the spent match book is sufficiently removed from the holder by bending it forward so as to release it from the spurs and then lifting it slidably from the pocket in which it seats.

It will be understood by those skilled in the art that the details of construction as herein illustrated and described, and the arrangement of parts, are by way of example and not to be construed as limiting the scope of the invention which is defined in the appended claims.

What I claim as my invention is:

1. Match book holder comprising a flat back member having a forwardly extending channel for supporting the base of a match book, a forwardly extending band adapted to encompass the match book above said base supporting channel, said band having a forwardly extending flange functioning as a fire guard, the front of said holder being formed with an opening between said base supporting channel and said encompassing band adapted to register with the striking surface of the match book, said opening being characterized by the absence of structure at its ends in the plane of the striking surface of the match book, which might impede the freedom of the striking stroke of the match, said back member being provided with forwardly extending penetrating lugs near its top adapted to impale the match book and inhibit tilting movement of the same.

2. Match book holder comprising a flat back member having a forwardly extending channel for supporting the base of a match book, a forwardly extending band adapted to encompass the match book above said base supporting channel, said band having a forwardly and upwardly extending flange along its lower edge functioning as a fire guard and as a guide to direct a match against the striking surface of the match book, said holder being formed with an opening between said base supporting channel and said encompassing band adapted to register with the striking surface of the match book, said opening being characterized by the absence of end structure in the plane of the striking surface of the match book which might impede the freedom of the striking stroke of the match, and said back member being provided with forwardly extending lugs adapted to inhibit tilting movement of the match book.

BENJAMIN L. BROOKS.
